LAP

Richard Groetchen, Chicago, Ill.

Application February 27, 1935, Serial No. 8,420

2 Claims. (Cl. 51—184.3)

This invention relates to a lapping or polishing tool which is designed for use in lapping, polishing or smoothing the interior of a perforation into which it can be inserted.

It has for one object to provide a lap of adjustable diameter. It has for another object to provide an adjustable mandrel for receiving a flexible lap. Another object is to provide the combination of the two in which the outside diameter of the lap is variable by adjusting the diameter of the mandrel or holder about which the lap is positioned.

Other objects will appear from time to time in the specification and claims.

The invention is illustrated more or less diagrammatically in the accompanying drawing, wherein:

Figure 1 is a side elevation of the lap and mandrel, the lap being in position in a perforation;

Figure 2 is a transverse section taken at line 2—2 of Figure 1 on an enlarged scale;

Figure 3 is a side elevation of the mandrel with the lap removed;

Figure 4 is a transverse section on an enlarged scale, taken at line 4—4 of Figure 3;

Figure 5 is a longitudinal section taken at line 5—5 of Figure 2, with the lap removed;

Like parts are designated by like characters throughout the specification and drawing.

1 is a piece of material which has been perforated as at 2. 3 is any suitable rotating device by means of which the lap is to be rotated. 4 is the shaft of the mandrel. As indicated particularly in Figures 3 and 5, it is tapered at its lower end as at 5. Adjacent its lower end and lying partially on the untapered portion is a threaded section 6. A keyway 7 may be cut in the lower end of the shaft 4. As shown it extends from the lower end through the threaded section. At its lower end the member 4 is provided with a threaded cavity 8, extending inwardly from its bottom, within which may be positioned a screw 9 having an enlarged head 10. A washer 11 is positioned about the screw and between the head 10 and the lower end of the member 4.

An interiorly threaded adjusting stop 12 is positioned upon the threaded portion 6 of the shaft 4. It may be provided with perforations 13 or any other suitable means by which it may be engaged by a tool so as to be rotated and thus adjusted along the shaft 4.

Positioned wholly or largely upon the tapered portion 5 of the shaft 4 is an expandible mandrel head 14. It is split, preferably from end to

end, as at 15 and is provided adjacent its upper end with a laterally extending flange 16. It is provided interiorly with a plurality of inwardly extending and preferably generally radial vanes 17. One or more of these vanes, as for example the vane 18, may be provided with an inwardly extending key 19 to fit within the keyway 7 to prevent rotation of the mandrel head with respect to the shaft. The inner faces of the vanes 17 are preferably tapered as indicated in detail in Figure 5. At their lower ends the vanes are cut away as at 20 to provide shoulders 21 against which the washer 11 fits as shown particularly in Figure 5.

Positioned about the outside of the mandrel head 14 is a flexible lap 22 which is preferably perforated by a series of perforations 23. The lap has an inwardly turned flange or edge 24, which lies within the slot 15 of the mandrel head 14. The lap is preferably made of some flexible and relatively soft material such as copper, and is given a spring shape so that it embraces the mandrel head closely and will conform to its size and shape, expanding as the head is expanded and contracting as it is contracted.

It will be realized that whereas I have herewith shown and described a practical operative device, nevertheless many changes might be made in the size, shape, number and disposition of parts without departing from the spirit of my invention and I wish, therefore, that my showing be taken as in a sense diagrammatic.

Particularly the material and shape of the lap might be almost infinitely varied and the invention is not limited to any particular type of lap member. Also the expandible mandrel head, while it is shown as made of a single piece having an end to end slot to permit ready expansion and contraction, might be made of other shapes, with one or more slots and they might or might not extend the full length of the mandrel head.

The use and operation of my invention are as follows:

The parts are assembled generally as shown in Figure 1. As illustrated in Figure 5 the adjustable mandrel head is shown in full lines, in approximately its uppermost position. To set the mandrel head for a given diameter the stop 12 is screwed up or down on the shaft 4 to the desired point. Then the screw 9 is screwed home and the washer on it, bearing against the shoulders 21 of the vanes 17 of the head 14, carries the head along the taper with the movement of the screw and so the head is moved along the taper

until its upper end contacts the stop 12. Further movement is prevented by the stop.

To change the position of the head the stop 12 may be moved upward and the screw 9 screwed further in, or else the screw 9 may be moved out and the stop rotated to move it downward. Thus the position of the expandible head 14 is determined by the position of the stop 12 and the screw 9. They determine the position and lock 10 the head.

The lap itself is flexible and preferably springy and is normally given an initial shape less in diameter than the minimum diameter of the adjustable mandrel head. It embraces the head 15 tightly. When the head is expanded by being forced further up along the tapered portion 5 of the shaft 4, the lap expands with it. When it is reduced the lap contracts with it.

The normal direction of rotation of the tool is 20 indicated by the curved arrow in Figure 2. The edge of the lap carrying the inturned portion 24 is the leading edge and the plain edge is the trailing edge.

With the parts assembled as shown in Figure 1 25 the tool as a whole is inserted in a perforation which is to be lapped, the desired lapping compound is put into the hole and the tool is rotated. In this manner the lapping operation is carried out and any desired adjustment in the diameter 30 of the lap is accomplished as above indicated, by moving the adjustable mandrel head up or down along the tapered portion 5 of the shaft 4.

I claim:

1. In a lapping device, a driving member constituting a mandrel shaft, said member being tapered at one end, and a mandrel head positioned upon said tapered shaft, an adjustable stop on the shaft and means comprising a screw and a laterally extending washer associated therewith, for drawing the mandrel head along the tapered portion and for holding it in contact with said adjustable stop, said mandrel head being split, 10 and hollowed to receive said screw and washer.

2. In a lapping device, a driving member constituting a mandrel shaft, said member being tapered and threaded at one end, and an interiorly tapered mandrel head positioned upon said tapered shaft, an adjustable stop on the shaft and means comprising a screw and a laterally extending washer associated therewith for drawing the mandrel head along the tapered portion and for holding it in contact with said adjustable stop, a flexible metallic sleeve, having a flange thereon, constituting an operating member removably mounted upon said mandrel head, said mandrel head being split, the flange of said flexible metallic sleeve being positioned in the split in said mandrel head, said sleeve extending about the mandrel head throughout the major portion of its periphery, one end of the sleeve being free to permit relative movement thereof with reference to 20 the mandrel.

RICHARD GROETCHEN.
